Charles A. Eck,

BY *Frank D. Weston*

ATTORNEY

UNITED STATES PATENT OFFICE.

CHARLES A. ECK, OF NEWARK, NEW JERSEY.

BRUSH-HOLDER AND BRUSH.

SPECIFICATION forming part of Letters Patent No. 673,516, dated May 7, 1901.

Application filed November 24, 1900. Serial No. 37,659. (No model.)

To all whom it may concern:

Be it known that I, CHARLES A. ECK, a subject of the King of Sweden and Norway, and a resident of Newark, in the county of Essex and State of New Jersey, have invented certain new and useful Improvements in Brush-Holders and Brushes, of which the following is a specification.

My invention relates to brush-holders and brushes for dynamo-electric machines; and its object is to provide a brush-holder and brush which will keep the latter in contact with the commutator with its full bearing-surface and at the same time have the pressure of the holder evenly distributed at all times, so as to wear the brush evenly, prevent sparking, and generally to yield a higher efficiency in its operation.

Other objects will appear farther on in the specification; and the invention consists of the hereinafter-described means pointed out in the claims.

In operating dynamo-electric machines it is of the utmost importance that the entire bearing-surface of the brush should be kept in contact with the commutator, so as to prevent uneven wear of the said brush, which is undesirable, as a sharp edge or ridge is sometimes formed thereby, which cuts into the commutator, and also for the reason that unless full contact is made the brush acts as an unsatisfactory conductor, breaking the current and causing sparking. As the commutator is a revolving body cylindrical in form, it presents a continuously-moving arc-shaped friction-surface to the brush, and the latter to make full and perfect contact must needs be in a position where the center line of its arc-shaped bearing-surface will at all times be coincident with a line radiating from the center of the circle describing the contacting arc of the commutator. In other words, the bearing-surface of the brush must at all times be concentric with the contacting arc of the commutator. In practice it has been found that even although the brush is perfectly adjusted and the pressure of the brush-holder evenly distributed when inserted into the latter, registering perfectly with its entire bearing-surface, it soon wears down unevenly owing to the somewhat irregular motion of the commutator, and the unsatisfactory condition stated above results. Heretofore it has been attempted to prevent this uneven con-

tact, pressure, and wear by supporting the brush rigidly and in such a manner that it is impossible for it to move circumferentially of the commutator. My invention, on the other hand, contemplates the supporting of the brush loosely, as with a joint, so as to allow enough play to enable the brush to adapt itself to any irregular motion on the part of the commutator, so that its bearing-surface will at all times be concentric with the contacting arc of the commutator. This may be accomplished either by supporting the brush loosely on a hinge or ball-and-socket joint or by supporting the brush rigidly on a loosely-pivoted brush-holder admitting of movement.

In the drawings I have embodied my invention in various forms, indicating the different constructions which may be used; but it will of course be understood that any and all constructions may be used embodying the invention herein set forth and that I do not limit myself to the exact means shown.

In the said drawings, Figure 1 shows a commutator with a brush-holder and brush embodying my invention. Fig. 2 is a side view of the same. Figs. 3, 4, 5, and 6 are detail views. Figs. 7, 8, 9, 10, and 11 are modifications.

Similar numerals of reference indicate corresponding parts in the different views.

I shall describe a brush-holder, brush, and adjacent elements embodying my invention and afterward point out the novel features in the claims.

1 indicates an armature-shaft with the commutator 2 mounted upon it.

3 is a stationary bar attached in any suitable manner to the motor and adapted to fit into the aperture 4 of the detachable holder 6 and fastened there by means of the screw 7, one surface 8 of the bar being made flat for that purpose. This holder 6 has a downwardly-extending projection 6^a, which carries the U-shaped spring 9, having fastened at its other end the bearing-joint 10, having the curved portion 10^a, adapted to fit into the brush 11, provided with the correspondingly-curved concavity 11^a. This concavity may extend only partially across the brush, as shown in Figs. 1 and 3, or it may have the concavity running its entire width, as shown in Fig. 4. To prevent displacement, the curved portion 10^a may be provided with a pin 10^b and the brush with a corresponding

concavity 11^c, as shown in Fig. 4. The holder 6 has also a split aperture 6^b, provided with the transverse tightening-screw 6^c and adapted to hold the guide-pin 6^d, provided with the 5 head or button 6^e. This guide-pin is adjustable and is adapted to act as a guide for the bearing-joint 10, the latter having to that end the aperture 10^c.

In connection with the brush and the bearing-joint there is still another point to be noted. The brush 11 is provided with a slot or concavity 11^d, extending all the way across the rear face, so that when the said brush is worn down to this slot it will break or split 10 and drop off and the motor stop, thus forcibly calling attention to the necessity of inserting a new brush, while the bearing-joint 10 is prevented from flying against the commutator by the button or head 6^e. The spring 9 is 15 also of a peculiar construction. It has been found that if a spring is made of a material which is a good conductor, such as copper, its elasticity is quickly destroyed by the electric current passing through the same. For this 20 reason I make my spring of two layers of material having different characteristics, one a good conducting material, such as copper, and the other of a material of indifferent conductivity and whose elasticity is not destroyed 25 by the current, such as steel. The conducting and elastic layers, respectively 9^a and 9^b, are so arranged that the conducting-layer contacts with the bearing-joint 10 and the portion 6^a, as shown, so that the circuit is un- 30 interrupted.

In Fig. 7 the peripheral movement of the brush is accomplished by forming the brush with a socket 12 and the holder with a rounded portion 12^a, adapted to fit into the same. In 40 this instance the pressure is exerted by means of the spring 12^b pressing on the movable member 12^c, sliding in the stationary member 12^d, the tension of the spring being regulated by means of the pin 12^e.

45 In Fig. 9 the brush is formed with a triangular ridge 13, extending transversely, and the bearing-joint with a triangular incision 13^a, while in Fig. 10 the brush has a cone-shaped portion 14, the bearing-joint having 50 correspondingly a cone-shaped socket 14^a.

In Fig. 8 the brush has a triangular incision 15 extending transversely and adapted to receive the dog 15^a, whose tension is regulated by a spring 15^b, adjustable by means of 55 the handle 1^c, adapted to be inserted into the notches 15^d in a well-known manner.

In Fig. 11 the brush is shown as being held rigid, while the holder is pivoted, as at 16, whereby the same result of peripheral play is 60 obtained.

Various other forms may of course be used to suit different requirements; but

What I claim, and desire to secure by Letters Patent, is—

65 1. The combination of a commutator and a brush adapted to break or split when worn to a predetermined but variable point, with a

brush-holder adapted to support said brush, means carried by said brush-holder adapted to hold the brush under tension against the 70 commutator, and means for limiting the movement of the tension means so that the latter will not contact with the commutator when the brush breaks, substantially as described.

2. The combination of a commutator and a 75 brush adapted to break or split when worn down to a predetermined but variable point, with a brush-holder, a bearing-joint carried by said brush-holder adapted to support the brush, means for holding said bearing-joint 80 under tension against the brush, and means for preventing the contact of the bearing-joint with the commutator when the brush breaks, substantially as described.

3. In a brush-holder, a tension-spring adapted to act as a conductor of the current, comprising two or more superposed layers of different character of materials, the current passing through one layer while the elasticity of the spring is maintained by the other layer, 90 substantially as described.

4. In a brush-holder, a tension-spring formed of two superposed layers of material, one layer acting as a conductor of the current the other layer preserving the elasticity of the spring, 95 substantially as described.

5. In a brush-holder a tension-spring formed of two superposed layers, one layer being of a good conducting material, the other layer of a material substantially indifferent to the electric current, so as to preserve the elasticity of the spring, substantially as described.

6. In a brush-holder a tension-spring formed with a conducting and a relatively indifferent conducting layer, for the purposes as set forth, 105 substantially as described.

7. In a brush-holder, the combination of a holder, a bearing-joint, a conducting tension-spring formed with a conducting and a relatively indifferent conducting layer connecting the two and so arranged that the conducting layer is in direct contact with both the holder and the bearing-joint, substantially as described.

8. In a brush-holder, a stationary support, 115 a detachable holder on said support, a downwardly-extending projection carried by said support, a U-shaped tension-spring on said projection, a bearing-joint for supporting the brush carried by said spring, an adjustable 120 horizontal guiding-bar carried by the holder at its upper end, an aperture in said bearing-joint for the insertion of said guiding-bar, and means carried by said bar limiting the movement of the bearing-joint, substantially 125 as described.

Signed at Newark, in the county of Essex and State of New Jersey, this 8th day of November, A. D. 1900.

CHARLES A. ECK.
